(57) **CLAIM**

The ornamental design for a scanning arrangement, as shown and described.

DESCRIPTION

FIG. 1 is a top side perspective view of a scanning arrangement showing our new design;

FIG. 2 is a first side view of the scanning arrangement of FIG. 1;

FIG. 3 is a second side view of the scanning arrangement of FIG. 1;

FIG. 4 is a third side view of the scanning arrangement of FIG. 1;

FIG. 5 is a fourth side view of the scanning arrangement of FIG. 1;

FIG. 6 is a top side view of the scanning arrangement of FIG. 1; and,

FIG. 7 is a bottom side view of the scanning arrangement of FIG. 1.

The broken lines show portions of a scanning arrangement that form no part of the claimed design.
